(57)

CLAIM

The ornamental design for a cleaning appliance, as shown and described.

DESCRIPTION

1. Cleaning appliance

FIG. 1.1 is a perspective view of a cleaning appliance, showing my new design;

FIG. 1.2 is another perspective view thereof;

FIG. 1.3 is a plan view thereof;

FIG. 1.4 is an opposite side plan view thereof;

FIG. 1.5 is a side elevation view thereof;

FIG. 1.6 is an opposite side elevation view thereof;

FIG. 1.7 is a front elevation view thereof; and

FIG. 1.8 is a rear elevation view thereof.
